(57) **CLAIM**

The ornamental design for an bidet mixer, as shown.

DESCRIPTION

FIG. 1 is a perspective view of an bidet mixer embodying our design;

FIG. 2 is a left side view thereof;

FIG. 3 is a right side view thereof;

FIG. 4 is a front view thereof;

FIG. 5 is a rear view thereof;

FIG. 6 is a top plan view thereof; and,

FIG. 7 is a bottom plan view thereof.

The broken lines in the drawings depict portions of the bidet mixer that form no part of the claimed design.
